(57) **CLAIM**

The ornamental design for a valve cone for a regulating valve, as shown.

DESCRIPTION

FIG. 1 is a perspective view from above showing my new design;

FIG. 2 is a perspective view from below of the valve cone for a regulating valve shown in FIG. 1;

FIG. 3 is a top plan view of the valve cone for a regulating valve shown in FIG. 1;

FIG. 4 is an underneath plan view of the valve cone for a regulating valve shown in FIG. 1;

FIG. 5 is a side view from one side of the valve cone for a regulating valve shown in FIG. 1; and,

FIG. 6 is a side view of the another side of the valve cone for a regulating valve shown in FIG. 1.
